US00D843954S

(12) **United States Design Patent** (10) **Patent No.:** **US D843,954 S**
(45) **Date of Patent:** **** Mar. 26, 2019**

(54) **TRANSMITTER**

(71) Applicant: **The Chamberlain Group, Inc.**, Oak Brook, IL (US)

(72) Inventors: **Kenneth F. Tomerlin**, Darien, IL (US); **Darryl P. De Wind**, West Olive, MI (US)

(73) Assignee: **The Chamberlain Group, Inc.**, Oak Brook, IL (US)

(**) Term: **15 Years**

(21) Appl. No.: **29/628,100**

(22) Filed: **Dec. 1, 2017**

Related U.S. Application Data

(62) Division of application No. 29/573,550, filed on Aug. 8, 2016, now Pat. No. Des. 813,825.

(57) **CLAIM**

We claim the ornamental design for transmitter, as shown and described.

DESCRIPTION

FIG. 1 is a perspective view of transmitter in accordance with our new design;

FIG. 2 is a left side elevation view of the transmitter of FIG. 1;

FIG. 3 is a right side elevation view of the transmitter of FIGS. 1-2;

FIG. 4 is a top view of the transmitter of FIGS. 1-3;

FIG. 5 is a bottom view of the transmitter of FIGS. 1-4;

FIG. 6 is a front elevation view of the transmitter of FIGS. 1-5;

FIG. 7 is a perspective view of transmitter in accordance with a second embodiment of our new design;

FIG. 8 is a left side elevation view of the transmitter of FIG. 7;

FIG. 9 is a right side elevation view of the transmitter of FIGS. 7-8;

FIG. 10 is a top view of the transmitter of FIGS. 7-9

FIG. 11 is a bottom view of the transmitter of FIGS. 7-10; and,

FIG. 12 is a front elevation view of the transmitter of FIGS. 7-11.

In the drawings, the broken lines depict portions of the transmitter that from no part of the claimed design.

1 Claim, 8 Drawing Sheets
